FLOATING BALANCED DOCTOR BLADE OR VANE

Gabriel A. G. Fazekas, Roslyn Heights, N.Y., assignor to The Farmingdale Corporation, Farmingdale, N.Y., a corporation of New York

Filed Sept. 26, 1956, Ser. No. 612,308

8 Claims. (Cl. 103—84)

This invention relates to a floating balanced doctor blade or vane and more specifically to such a blade designed for use in a fluid pump or the like operating on the viscosity principle, as exemplified by the pumps shown in Modrovsky and Sherwood application Ser. No. 465,078, filed Oct. 27, 1954, now Patent No. 2,777,394, and in Fazekas and Modrey application, Ser. No. 563,750, filed Feb. 6, 1956, of which latter application this is a continuation-in-part.

It is an object of the invention to provide such a blade which will form a sufficiently positive stop for the fluid entrained by relative motion of a rotor and a stator separated by a small clearance space, while ensuring that the blade will retain an adequate measure of mobility in order to be self-adjusting to rapidly or slowly changing conditions. That is, the blade should close, to a considerable extent, the clearance space but must be free to float in a hydraulically balanced state, and not be rigidly fixed in position or subject to binding or jamming under any possible operating conditions.

In the present case, the desired result is attained by the provision of a floating balanced blade designed to operate in a slot which is combined with the pressure fluid discharge port and constitutes a portion thereof. This not only eliminates the danger of the blade's sticking or jamming in a fixed and incorrect position with respect to its slot and to the parts providing the clearance space, but also minimizes the space lost as compared to arrangements in which the supply and delivery ports both connect directly with the clearance space.

Practical embodiments of the invention are shown in the accompanying drawings, wherein:

Fig. 1 represents a transverse sectional view of a floating balanced blade, mounted in a slot in a stator and designed to close adequately the clearance space between the stator and a rotor;

Figs. 1a and 1b represent detail modifications of the blade, in respect of the cross-sectional shape of the bottom part thereof;

Fig. 2 represents a transverse sectional view of a modified blade arrangement, including a spring;

Fig. 3 represents an elevation view of the blade and spring, partly in section on the line III—III of Fig. 2;

Fig. 4 represents a view, similar to Fig. 1, but showing an alternative arrangement of the delivery port, and

Fig. 5 represents a detail elevation of a portion of the spacing plate 3 as viewed from the right of Fig. 1 or Fig. 2, for instance.

Referring to the drawings, and particularly Fig. 1 thereof, a rotor R is assumed to be moving in the direction of the arrow, with respect to a stationary casing or stator C', C'' (corresponding to the casing halves 1 and 2 in said application Ser. No. 563,750) with a clearance K between the adjacent surfaces of said rotor and stator, all as more fully explained in the copending applications cited above. A fluid of some viscosity (e.g., an oil to be pumped) is supplied to the clearance at a point downstream from a wiper or doctor blade 1 (constituting a fluid arresting means) and is drawn from said clearance, for delivery

2

wherever desired, through the port P. The terms "downstream" and "upstream" wherever used herein designate directions or locations considered with reference to the direction of movement of the rotor relative to the stationary casing, as indicated by the arrow on the rotor. The blade 1 is shown as being generally rectangular in cross-sectional form and as being freely mounted with a close sliding fit in the slot 2 formed, for instance, in the casing half C'. The casing halves C', C'' are shown as being spaced apart by a plate 3 corresponding, to this extent, to the "inlet spacer bar 4" of said application Ser. No. 563,750; the plate 3 is cut away along its downstream edge to form a plurality of inlet channels 3' communicating laterally with an elongated supply passage S in the casing C'' and downwardly with the clearance space. It will be noted that the fluid is thus admitted to the clearance space in a zone as near as possible to the doctor blade, so as to be subjected most efficiently to the entrainment effect.

The plate 3 forms the downstream wall of the slot 2 and may be made of relatively wear-resistant material so as to maintain constant the cross-sectional shape of the slot. Said slot has a vertical depth somewhat greater than the corresponding dimension of the blade so that there is an appreciable clearance between the top of the blade and the inner (top) wall 2' of the slot. The delivery port P communicates with the slot, preferably through said wall 2' as shown.

The blade may be of extended length, as indicated in Fig. 3, and the slot is of corresponding length. The bottom surface of the blade is shown in Fig. 1 as being divided by the longitudinal groove 4 (which may be semi-circular in cross-section, as shown, or may have any other convenient form) into separate narrow lands 5' and 5'', the land 5'' along the downstream edge of the blade being capable of resting on the surface of the rotor, while the land 5' along the upstream edge of the blade must always remain out of contact with the rotor surface. That is, the clearance between 5'' and the rotor surface is at all times less than the clearance between 5' and said surface. Possible alternative profiles are illustrated in Fig. 1a, where the bottom surface 13 of the blade is "stepped," and in Fig. 1b where the bottom surface 14 is beveled, there being in each case a narrow land 15 or 15', respectively, along the downstream edge corresponding to the land 5'' of Fig. 1. The form shown in Fig. 1b will be recognized as corresponding to that appearing at 5 in Fig. 2 of application Ser. No. 563,750.

The upstream side surface of the blade is provided with an elongated recess 6, leaving upper and lower horizontal lands 7' and 7'', respectively, through which are formed vertically disposed grooves 8', 8''. The downstream side wall of the blade is also provided with an elongated recess 9, between upper and lower horizontal lands 10', 10'', respectively. A plurality of small holes 11 connect the recess 6 and the recess 9.

It will be appreciated that, in the operation of a pump, for instance, embodying the structure just described, the fluid entrained by the rotor will form a wedge at an elevated pressure beneath the blade (having a lifting effect thereon) and will flow upward through the grooves 8', 8'' to the outlet port P, while creating in the upper part of the slot a force acting downwardly on the top of the blade to counteract the lifting force of the wedge thereunder. At the same time part of the fluid will pass through the holes 11 and create a cushion of pressure on the downstream side of the blade (recess 9 and lands 10', 10'') which balances horizontally the pressure on the upstream side (recess 6 and lands 7', 7'').

Upon initially putting in operation a pump having such a blade and output port arrangement as described above, there is no hydraulic force acting on the top of the blade to match the lifting force of the wedge under

the blade; the blade may thus be lifted to a degree such as to make it quite ineffective or at least to delay its reaching the point of effective operation, which depends on limiting the pressure drop between the upstream bottom corner of the blade and the entrance of the outlet port to a value ensuring the application of a force to the top of the blade at least equal to the lifting force of the wedge. Such a condition is possible because, for instance, the pressure on the land 5" is less than the maximum due to leakage of the fluid past said land to a zone of zero (inlet) pressure; thus the average pressure on the bottom of the blade may be less than the average (and substantially uniform) pressure on the top.

The starting problem can be overcome by providing a spring 12 (Figs. 2 and 3) disposed between the top of the blade and the upper wall 2' of the slot in order to bias the blade toward the rotor. Such a spring, which may be in the form of a leaf of clock-spring material, need not exert any great amount of force (compared to the pressures of several thousand p.s.i. which pumps of this type can deliver) so long as it is sufficient to prevent any serious degree of lifting of the blade at the beginning of operation and to maintain the total downward force on the top of the blade (hydraulic plus spring) at a value in excess of the lifting force beneath it, under all contemplated conditions of operation.

The spring 12 may be undulated (Fig. 3) or provided with appropriately placed longitudinal slots, or both, in order to eliminate the possibility of its blocking materially the entrance to the delivery port P, when the latter is in the position shown in Figs. 1 to 3.

While the outlet port P is shown as opening through the top wall 2' of the slot, it could, if desired, open through the side wall of the slot on the upstream side, e.g., opposite the recess 6, the top wall being then solid and the upper part of the slot being a "dead end" pocket in which a cushion of pressure fluid is maintained at a pressure corresponding to that in the recess 6, all as illustrated in Fig. 4 (otherwise similar to Fig. 1).

While the terms "top" and "bottom" have been used herein for convenience, referring to the parts as shown in the drawing, it will be understood that pumps or the like in which such blades are used may employ a plurality of blades disposed symmetrically (or otherwise) and mounted in any position whatever with respect to the earth's surface—upside down, sideways, on end, etc. As an order of magnitude, the blades presently contemplated are conceived as having a height of about one inch or less, a length of a few inches, and being adapted for use in connection with a viscous fluid such as oil in a clearance space measured in thousandths or hundredths of an inch, the clearances and certain other dimensions being obviously greatly exaggerated in the drawings, for purposes of illustration only.

It will be understood that various changes may be made in the form, construction and arrangement of the

several parts without departing from the spirit and scope of the invention.

What I claim is:

1. In a pump or the like having a stator and a rotor separated by a clearance of substantially uniform radial depth and constant volume and provided with means for supplying a viscous fluid to said clearance, a fluid arresting means and mounting therefor comprising, a slot formed in said stator and opening into said clearance, 10 an outlet port communicating with said slot through the inner wall thereof, a doctor blade floating freely in said slot, said blade having a generally rectangular cross-sectional form and being provided with grooves so disposed as to permit the passage of fluid past the blade on its upstream side from the clearance to the outlet port, the blade being further provided on its side faces with longitudinally extending recesses bounded adjacent the top and bottom of the blade by relatively narrow flat lands, and the grooves extending across the lands on the upstream side face of the blade.
- 15 2. A fluid arresting means and mounting therefor according to claim 1 in which the blade is provided with at least one passage connecting the recess on the upstream side face with the recess on the downstream side face.
- 20 25 3. A fluid arresting means and mounting therefor according to claim 1 which includes a spring so disposed as to bias the blade toward the rotor.
- 25 4. A fluid arresting means and mounting therefor according to claim 3 in which the spring is located between the top surface of the blade and the inner wall of the slot.
- 30 5. A fluid arresting means and mounting therefor according to claim 1 in which the surface of the blade facing the rotor comprises a zone adjacent the downstream edge of the blade which lies closer to the surface of the rotor than does any other part of said blade surface.
- 35 6. A fluid arresting means and mounting therefor according to claim 5 in which the surface of the blade facing the rotor is longitudinally grooved.
- 40 7. A fluid arresting means and mounting therefor according to claim 5 in which the surface of the blade facing the rotor is stepped.
- 45 8. A fluid arresting means and mounting therefor according to claim 5 in which the surface of the blade facing the rotor is at least partially beveled.
